STORM WINDOW FASTENER

John H. Widmer and Carl T. Smith,
St. Paul Park, Minn.

Application July 22, 1946, Serial No. 685,497

10 Claims. (Cl. 292—275)

1

Our invention relates to an improvement in storm window fastener wherein it is desired to provide a means of holding a storm window in adjusted angular relation relative to its frame.

An object of the present invention lies in the provision of a fastener which includes readily separable parts to permit the fastener to be disengaged when the storm window is removed.

A further object of the present invention lies in the provision of a fastener by means of which a storm window may be frictionally held in adjusted position.

A feature of the present invention resides in the provision of a rod pivotally attached to a storm window and a cooperable channel pivotally supported on the window frame. The rod is frictionally engaged in the channel in such a way that it may be readily removed therefrom in practice.

A feature of the present invention resides in the provision of a rod pivotally attached to a window and a channel pivotally supported on the window frame in such a manner that the pivots of the rod and of the channel are coaxial when the window is in closed position. As a result the rod and channel may be pivoted in unison to extend parallel to the window to lock the storm window in closed position.

A further feature of the present invention resides in the provision of a spring element for frictionally engaging the rod and in the provision of a pair of spring ears in conjunction therewith for holding the rod engaged in the spring element. Thus the spring element serves the double function of frictionally engaging the rod to normally hold the rod from movement relative to the same and also to hold the rod engaged therewith.

An added feature of the present invention lies in the provision of a means of adjusting the tension of the spring clip against the rod. As a result compensation for wear is provided and the spring tension may be increased when found necessary or desirable.

A further feature of the present invention lies in the provision of a stop for limiting the pivotal movement of the arm and channel in one direction. Accordingly in opening the window the arm and channel may be swung about their common axes in unison until the channel engages the adjacent stop whereupon the channel and rod are properly positioned to permit the opening of the window. This feature is extremely desirable as in opening the window it is necessary that the rod and channel extend initially in

2

line with the direction of movement of the window.

These and other objects and novel features of our invention will be more clearly and fully set forth in the following specification and claims.

In the drawings forming a part of our specification:

Figure 1 is a front elevational view of our storm window fastener showing the construction thereof.

Figure 2 is a sectional view through a portion of the storm window and its frame showing the relative relation between the parts of the fastener when the window is opened.

Figure 3 is an elevation view of the bracket mounted on the window frame showing an end view of the rod supported therein.

Figure 4 is a perspective view of the spring element supported within the channel to frictionally engage the rod.

The fastener A is mounted upon a storm window such as 10 which is pivotally supported in its frame 11. Usually a fastener A is provided on each side of the window. For the purpose of illustration, but one of the fasteners is illustrated.

The fastener A includes one portion which is mounted upon the storm window 10 and a second portion which is mounted upon the frame 11. As will be later described in detail the two parts of the fastener are relatively separable to permit the storm window to be readily removed from its frame for storage during warm weather.

A bracket 12 is supported upon the window 10 as best illustrated in Figures 1 and 2 of the drawings. The bracket 12 is preferably of channel shaped formation including a base plate 13 and a pair of upstanding parallel side plates 14. Screws 15 or other suitable fastening means extend through the base plate 13 to hold the bracket 12 to the margin of the window 10. Apertures 16 are provided in the side plates 14 for pivotally supporting the rod 17 in the manner later described in detail.

The rod 17 is substantially L-shaped in form having a short end portion 19 bent at substantially right angles to the remainder of the arm. This short end portion 19 extends through the apertures 16 in the side plates 14 and is pivotally supported thereby. The extremity of the angular portion 19 is flattened as indicated at 20 to hold the rod engaged in the apertures 16.

Thus it will be obvious that the rod 17 may pivot about a horizontal axis within the aper-

tures 16. This permits the rod 17 to assume various angularities relative to the window 10.

A stile plate 21 is secured to the frame 11 of the window 10. This stile plate 21 includes a pair of aligned end portions 22 and an off-set center portion 23. The stile plate 21 is attached to the surface of the window frame by screws 24 extending through the aligned end portions 22 thereof.

A channel member 25 is pivotally secured by means of a pivot 26 to the off-set portion 23 of the stile plate 21. The channel member 25 includes a base 27 and opposed parallel sides 29 and 30. As best illustrated in Figure 1 of the drawings the sides 29 and 30 are partially cut away adjacent the pivoted end of the channel although this construction is not entirely essential. The pivot 23 is arranged on a horizontal axis and the stile plate 21 is so mounted on the frame 11 that in closed position of the window 10 the axis of the pivot 26 coincides with the axis of the pivoted end portion 19 of the rod 17.

A spring clip 31 is supported within the channel 25, this spring clip being held in proper position by the pivot 26 which extends through the base 32 of the spring clip. The clip 31 is generally similar in shape to the channel 25 and is confined within the walls of this channel 25. The spring clip 31 includes the base 32 and side walls 33 and 34. Adjacent the base 32 these side walls 33 and 34 fit snugly within the side walls 29 and 30 of the channel 25. Each side wall, however, is provided with an inwardly projecting longitudinal rib, these ribs being indicated at 35 and 36 respectively. The free edge portions 37 and 39 of the side walls 33 and 34 are spaced inwardly from the side walls 29 and 30 of the channel bracket so as to permit the spring element 31 to spread an amount necessary to receive the arm 17.

A pair of inwardly bent lips 40 and 41 are provided on the free edge portions 37 and 39 of the side walls 33 and 34, these lips acting to hold the arm 17 engaged between the side walls of the spring clip 31. These lips 40 and 41 spread apart to permit insertion or removal of the arm 17 and tend to hold the arm engaged between the side walls of the spring clip when once in place. The manner in which the ears engage about the arm 17 is best indicated in Figures 2 and 3 of the drawings.

In order to provide an adjustment for compensating for wear of the spring clip we provide a set screw 42 extending through one or both of the channel walls 29 and 30. The set screw 42 engages the outer surface of a side wall 33 or 34 of the spring clip 31 to urge this side wall against the rod 17. By this means the frictional engagement between the spring clip 31 and the arm 17 may be adjusted.

When the fastener A is in the position shown in Figure 1 of the drawings, the storm window is locked from outward movement because of the fact that the channel 25 and arm 17 engaged thereby are substantially parallel to the storm window 10 and thus the arm can not be moved longitudinally of the channel by an outward force upon the window. Therefore in opening the window, it is first necessary to swing the arm 17 and the channel 25 in unison until the arm 17 extends substantially in the direction of movement of the window. In other words from closed position the bracket 12 on the storm window moves in a substantially horizontal direction. Accordingly the arms 17 are preferably swung

into substantially horizontal position before the window 10 is swung outwardly. In order to position the channel 25 and arm 17 supported thereby in substantially horizontal position, we prefer to provide a lug such as 43 on the stile plate 21 which limits upward pivoting of the channel 25. Thus the arm 17 may be swung upwardly until the channels 25 engage the lugs 43 whereupon the bracket is properly positioned to permit outward swinging of the window 10. This outward swinging of the window is limited by flattening the end 44 of the rod 17 so as to limit the slideable movement of the rod in the channel 25.

When the window 10 is in open position the arms 17 may be disengaged from the spring clips 31 within the channels 25 by flexing the arms 17 inwardly the necessary amount to clear to disengage the arm from the spring clip. The arms 17 either flex sufficiently to permit this disengagement or the pivoted ends of the arm 17 are pivotally supported with sufficient play to permit this disengagement.

In accordance with the patent statutes we have described the principles of construction and operation of our storm window fastener, and while we have endeavored to set forth the best embodiment thereof, we desire to have it understood that obvious changes may be made within the scope of the following claims without departing from the spirit of our invention.

We claim:

1. A storm window fastener for connecting a pivotally supported window to its frame, the fastener including an arm pivotally supported by the window, a channel bracket pivotally supported by said frame, and a channel shaped spring element within said channel bracket for frictionally engaging said arm, said spring element having a pair of spaced sides and a base, the arm being engageable and disengageable therefrom on movement toward or away from said base, the pivot connecting said arm to the window and pivotally connecting said channel bracket to the frame being substantially coaxial in closed position of the window.

2. A storm window fastener for connecting a pivotally supported window to its frame, the fastener including an arm pivotally connected to the window, a channel bracket pivotally supported to said frame, a channel shaped spring element having parallel sides and a connecting base supported within said channel bracket and frictionally engaging said arm, and means for urging one side of said channel shaped spring element toward the other for adjusting the tension of said spring element.

3. A storm window fastener for connecting a pivotally supported window to its frame, the fastener including an arm pivotally connected to the window, a channel bracket pivotally supported to said frame, a channel shaped spring element having parallel sides and a connecting base supported within said channel bracket and frictionally engaging said arm, and means for urging one side of said channel shaped spring element toward the other for adjusting the tension of said spring element, the pivots connecting said arm to said window and connecting said channel bracket to said frame being substantially coaxial in closed position of the window.

4. A storm window fastener for connecting a pivotally supported window to its frame, the fastener including an arm pivotally connected to the window, a bracket pivotally supported to said frame, the axes of said pivots being parallel,

said bracket comprising an elongated body pivoted to the frame at one end and having means thereon at the other end thereof slidably engaging said arm, said means holding said arm parallel to the longitudinal axis of said elongated body to intersect the axis of the pivotal connection between said bracket and said frame, the pivotal axes of said arm and said bracket being movable into alignment for pivotal movement about both axes simultaneously in closed position of the window.

5. The structure of claim 4 and including a spring friction means on said bracket engaging said arm.

6. The structure of claim 4 and including a channel shaped end on said elongated body forming said arm holding means.

7. The structure of claim 4 including a channel shaped end on said elongated body forming said arm holding means, and a channel shaped spring element within said channel shaped end removably engaging said arm under spring tension.

8. The structure of claim 4 including a stile plate on said frame to which said bracket is pivotally attached, and a stop shoulder on said stile plate limiting pivotal movement of said bracket.

9. A storm window fastener for use in connecting a pivotally supported window to its frame, the fastener including an arm pivotally connected to the window, a channel bracket pivotally supported to the frame, said channel bracket having spaced sides and a connecting base and being designed to removably and slidably support the arm between the spaced sides, and retaining means on said channel bracket between said spaced sides and movable toward or

away from said sides and frictionally engaging said arm to hold the arm between said spaced sides, said arm being disengageable from the bracket upon movement away from said base.

10. A storm window fastener for use in connecting a pivotally supported window to its frame, the fastener including an arm pivotally connected to the window, a channel bracket pivotally supported to the frame, said channel bracket having spaced sides and a connecting base and being designed to removably and slidably support said arm between the spaced sides, retaining means on said bracket for frictionally engaging said arm to hold the arm between said spaced sides and disengageable from the bracket upon movement away from said base, the pivots connecting said arm to the window and connecting said channel bracket to the frame being substantially co-axial in closed position of the window.
